CONTAINER

Robert P. Bemiss, San Francisco, Calif., assignor
to Bemiss Corporation, a corporation of California

Application September 8, 1936, Serial No. 99,725

5 Claims. (Cl. 206—46)

This invention relates to a new and useful container, particularly one to be utilized in the packaging of edibles, such as cookies, cakes, biscuits, nuts, fruit, candy, raisins and the like. These products are ordinarily packed fresh from the oven or process. In this condition they contain considerable moisture and, in some instances, are hot and therefore occupy a considerably larger volume than when they are cold.

At one time it was the practice to pack such commodities upon a sheet of strawboard or fiberboard. However, this practice was not successful because moisture condensed upon the transparent wrappers, obscuring the products and making the package unsightly. In addition, when the products cooled and shrank, the wrapper would become loose because, while it had been initially drawn tight over the products, the products, upon shrinking, occupied less volume and did not stretch the wrapper. This made an unsightly package, one giving the appearance of an old package. Since even a suggestion of age and staleness is highly undesirable in the trade, this manner of packing was not successful.

In accordance with my invention I provide a package in which the condensation of moisture is obviated, and, at the same time, the wrapper is kept stretched and taut so that an acceptable package is provided. This package I am able to provide by utilizing a backing of corrugated paper, the backing being provided in a particular manner to accomplish the ends of the present invention.

It is in general the broad object of the present invention to provide a novel package for edible products.

The invention includes other objects and features of advantage, some of which, together with the foregoing, will appear hereinafter wherein I have disclosed certain preferred ways in which I practice my invention. In the drawings accompanying and forming a part hereof I have disclosed certain packages to illustrate my present preferred practice. However, it is to be understood that the invention is not to be limited to these but is to be accorded a range of equivalents in accordance with the claims.

In the drawings, Figure 1 is a perspective view illustrating a package embodying features of the present invention.

Figure 2 is a section taken along the line 2—2 of Figure 1.

Figure 3 is another perspective view illustrating a box construction.

Figure 4 is a plan view of the corrugated back

before assembly into the box such as shown in Figure 3.

Figure 5 is a section taken on the line 5—5 of Figure 4 to illustrate the corrugated paper construction.

Figure 6 is another perspective view showing how cookies can be packed successfully.

Figure 7 is a section taken on the lines 7—7 of Figure 6.

Figures 8, 9 and 10 are respectively a perspective, a plan view and a section on line 10—10 of Figure 8, showing another carton.

In accordance with this invention, I utilize corrugated paper. This material, as appears in Figure 5, is made up of a base strip 11 and a corrugated strip 12 secured to the base strip by a suitable adhesive and formed in a manner well known in the art. This material is relatively light and inexpensive to manufacture and yet provides resiliency and strength.

In accordance with this invention, I take a sheet of corrugated paper 13 and, to provide the structures shown in Figures 1 and 2, provide score lines 14 and 15 therein. The corrugated strip is then bent in either direction upon the score lines 14 and 15, and sides 16 and 17 are formed. The products, in this case small cookies or cakes, indicated by numeral 18, are placed upon the base or smooth side of the corrugated strip, the ends 16 and 17 being bent back upon the strip. Under tension, the transparent cover 19 is then placed over the strip and is secured thereto, usually to the back, to provide a substantially airtight package. Subsequently, even if the products cool and shrink in size, it will be found that the transparent material 19 has been kept taut over the products. This is because the sides 16 and 17 tend to straighten out or unbend. As the products cool they move slightly, exerting a constant tension upon the transparent material which has been stretched initially between them.

As suitable transparent material I can use Cellophane, glassine, or other transparent material as is usually employed in the art.

The package disclosed also prevents the condensation of moisture upon the interior surface of the transparent material. Apparently this is due to the air circulation permitted by the plurality of conduits provided by the corrugated material.

In that form of the invention shown in Figures 3 and 4, a strip 21 of corrugated paper is provided with score lines 22 and 23 parallel to each other and extending transversely to the corrugations. Score lines 24 and 25 are provided ad-

jacent the ends of the strip and extend parallel to the corrugations so that the strip can be suitably bent into the form of the box as appears in Figure 3. I prefer that the score lines 22 and 23 5 beyond the score lines 24 and 26 be so deep as to actually sever the corrugated paper so that end sections 27 are provided which, when turned into position, engage end areas 28 to form a box structure. The ends 27 and 28 can be secured together 10 or left unsecured, as desired.

In that form of the invention shown in Figure 6, a bag of transparent material is provided, the bag being indicated by numerals 31. The corrugated backing strip or liner, indicated 15 by numeral 32, is substantially rectangular in form having a major axis and a minor axis substantially 90° to each other, the corrugations extending transversely to the major axis of the backing strip or liner. Ordinarily, this strip is 20 inserted with the corrugations uppermost, so that when the cookies are inserted they engage the corrugations and do not slide, although the strip can be placed in the bag with the smooth side against the products. Packing of the cookies to 25 an undue extent in the bottom of the bag is not encountered if they engage the corrugated face.

The corrugated strip 32 inserted in the bag 31 is also bent slightly upon itself so that when the products are inserted the strip of corrugated material is in tension and exerts a stretching effect 30 at all times upon the transparent bag 31 to maintain the bag taut over the products. In Figure 6, I have indicated this bending and its position by the letter M, the sheet being curved 35 slightly in the bag about the crease line M—M. The wrapper can be secured to the back face of strip 32 if it is desired to economize on wrapping material.

In Figures 8, 9 and 10 I have shown a carton 40 embodying the features of the invention. In this form I manufacture a continuous strip of corrugated material, severing the strip at edges 36 and 37 and creasing it at 38, 39 and 40 so that the severed strip can be bent into a tubular sleeve 45 with edges 36 and 37 suitably secured together. One face of the sleeve is cut with an H cut 41, the H being deep but leaving uncut portions 42.

In use, the sleeve, cut and joined, is readily handled and shipped flat. When it is to be filled, 50 the sleeve is unfolded and H sections 43 depressed. The corrugations of each H section engage the corrugations of the bottom section and lock the two together, the sections bending easily along the proper corrugations. The box thus formed is 55 filled with the commodity. Since the H sections provide rigid ends, the carton can be wrapped with a wrapper 44 on a standard wrapping machine, the wrapper being sealed at the box ends. This enables a saving in wrapping material to 60 be made.

The wrapper, Cellophane, or another regenerated cellulose material, or glassine, can be used as the wrapper, being stretched over the box.

It is believed to be apparent that the invention 65 disclosed can be embodied in various other useful forms to provide advantageously employed containers for the products indicated and those of a like nature.

What I claim as new and desire to secure by Letters Patent is:—

1. A package for products comprising a flat sheet of corrugated paper for supporting products on the corrugated face thereof, and a wrapper of transparent material stretched over said products and said sheet to retain products on said sheet, said sheet being folded along a line substantially at the middle of said sheet and extending transversely to corrugations in said paper 10 whereby said sheet is bowed upon itself to stretch said wrapper.

2. A package for products comprising a transparent baglike container, and a substantially flat sheet of corrugated paper positioned in said container to provide a substantially flat side in said container with corrugations in said sheet extending in one direction, said sheet being bent slightly upon itself in a direction transverse to the direction of the corrugations to stretch said container over said products.

3. A package for products comprising a transparent baglike container, and a substantially flat sheet of corrugated paper positioned in said container to provide a substantially flat side in said container with corrugations in said sheet extending in one direction and uppermost in said container to provide a rough surface for engagement with products in said container, said sheet being bent slightly upon itself in a direction transverse to the direction of the corrugations to stretch said container over said products.

4. A package for products comprising a sheet of corrugated paper bent upon itself in a direction transverse to that of the corrugations to provide opposite terminal edge portions at an angle to each other and tensioned with respect to each other through the portion of the sheet intermediate said terminal edge portions whereby said portions tend to return freely to that position 40 which said portions occupy when the sheet is flat, and a transparent wrapper extended about said sheet and over products supported on a face of said sheet and resisting return of said tensioned edge portions whereby said wrapper is maintained 45 taut over said products.

5. A package liner for use in a package wherein a plurality of products are carried in said package on one face of said liner with an outer covering for said products stretched by said liner over 50 said products and holding the latter tautly in place, said liner consisting of a substantially flat sheet of corrugated paper rectangular in form, said sheet having a major axis and a minor axis substantially 90° to each other, the corrugations 55 in said paper running substantially transverse to said major axis, and a crease line constituting a bending zone extending parallel to the major axis at or near the mid-point of said minor axis, the areas on either side of the crease line being relatively rigid in a direction transverse to the major axis, the width of said liner along its minor axis being such that when in place in said package the liner stretches the outer covering over products supported between the liner and said 65 covering.

ROBERT P. BEMISS.
